GARMENT CONSTRUCTION

Ernest G. Dann, New York, N. Y.

Application May 25, 1933, Serial No. 672,784

19 Claims. (Cl. 2—93)

This invention relates to a garment construction and more particularly to a belt construction for garments or the like.

One of the objects of this invention is to provide a belt construction which will be simple, practical and thoroughly reliable in operation. Another object is to provide a construction of the above character which may be economically manufactured with a minimum amount of labor. Another object is to provide a construction of the above character which may be readily applied to various garments as now used without making any radical changes in the construction and design thereof. Another object is to provide a construction of the above character which will be pleasing in appearance and from which ugly or cumbersome parts will be eliminated. Another object is to provide a construction of the above character wherein the belt may be reliably maintained in an operative position without accidental displacement and yet may be easily removed. Another object is to provide a construction of the above character which will maintain a belt in a proper and desirable position with respect to the garment at all times. Other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which are shown several of the various possible embodiments of my invention,

Figure 1 is a fragmentary back elevation of a garment having the preferred form of my belt construction applied thereto;

Figure 2 is an enlarged plan view, partially fragmentary, of certain of the parts of my belt construction;

Figure 3 is an enlarged vertical sectional view taken along the line 3—3 of Figure 2;

Figure 4 is an enlarged vertical sectional view taken along the line 4—4 of Figure 2;

Figure 5 is a plan view of a portion of a belt used in another embodiment of my invention;

Figure 6 is a vertical sectional view of the belt shown in Figure 5 secured to a garment or the like;

Figure 7 is a vertical sectional view of a belt, together with other means for attaching it to a garment constituting another embodiment of my invention, and

Figure 8 is a fragmentary plan view of a por-

tion of a garment having this embodiment of my invention applied thereto.

Similar reference characters refer to similar parts throughout the several views of the drawings.

As conducive to a clearer understanding of certain features of this invention, it might here be pointed out that belts for garments, as, for example, robes, dresses, or the like, have often been the object of considerable difficulty and annoyance to the wearer. Usually, belts are secured to such garments about the waist portions thereof by one or more loops secured to the rear of the garment through which the belt passes. Thus, the belt is free to slide through the loops and in use often becomes dislodged from the loops thus necessitating its replacement and, furthermore, the belt may become entirely dislodged from the loops and lost in this manner. It is also true that belts for garments of this character are often made from flexible material substantially similar to the material from which the garment is formed, and, due to the movement of the wearer and also twisting of the belt when securing it in position, the belt becomes rumpled and distorted instead of lying flat against the garment as is desirable. One of the various objects of this invention is to provide a construction in which the several difficulties hereinabove mentioned as well as many others will be successfully and practically overcome.

Referring now to Figure 1 of the drawings, there is shown a robe or the like generally indicated at 10 as worn in use. Encircling robe 10 is a belt 11 passing through suitable loops generally indicated at 12 and 13 and thus held in position substantially about the waist portion of the robe. Belt 11 may be of any suitable construction having its opposite ends meeting at the front of the garment and secured together by any desirable means. Garments, such as robe 10, are usually made from some flexible material and I prefer to form belt 11 from a material having like characteristics.

As more clearly shown in Figure 2, belt 11 has formed therein a longitudinal slot 14 substantially adjacent loop 12 and preferably at right angles thereto. I prefer to locate slot 14 so that its ends are substantially equidistant from loop 12 when belt 11 occupies its normal operative position. Preferably the edges of slot 14 are reinforced as, for example, by way of stitches of any suitable character generally indicated at 15.

As better shown in Figures 3 and 4, loop 12 comprises two thicknesses of material 16 and 17 folded back upon each other and suitably stitched

together by way of stitches 18. The opposite ends of loop 12 are also bent back upon each other and stitched to robe 10 by stitches 19. Thus, loop 12 is reliably secured to the robe against accidental displacement which might be caused by the incidents of practical use. Extending through slot 14 from robe 10 is a shank 20 which may be secured to the robe in any convenient manner as, for example, by way of a head 21.

10 A button 22 is connected to the opposite end of shank 20 so that it may be slipped through a suitable buttonhole 23 (Figure 4) formed in thickness 17, thus holding loop 12 down upon belt 11 and yet being concealed from view. Of course, hole 23 may extend through both thicknesses 16 and 17 of the material so that button 22 appears on the outside of the loop, but concealing the button as hereinabove described has certain unique advantages.

20 Suitably disposed between thicknesses 16 and 17 is a pair of reenforcing parts 24 and 25 preferably located adjacent the opposite sides of the loop. Parts 24 and 25 may be formed from any suitable flexible material as, for example, celluloid or whalebone, and are preferably held in position spaced from button 22 by stitches 26 extending through thicknesses 16 and 17 of the loop on the opposite sides of part 24 and on the side of part 25 opposite stitches 18. Accordingly, parts 24 and 30 25 act to maintain loop 12 in an extended and flatwise position with respect to robe 10 and yet do not hinder the insertion or removal of button 22 from hole 23.

35 Preferably there is secured to that portion of robe 10 opposite loop 12, a strip of material 27 characterized by its relatively smooth surface. Thus, strip 27 may be made from silk, rayon, or the like. Also, the under side of loop 12 has secured thereto a strip of material 28 similar to strip 27. Thus, frictional resistance to the passage of belt 11 through loop 12 is reduced materially.

40 Turning back to Figure 1, loop 13 is substantially similar in construction to loop 12, as described above, and belt 11 has a slot 29 formed therein occupying a position with respect to loop 13 similar to the position occupied by slot 14. Thus, the opposite ends of slot 29, when belt 11 is in normal position, are substantially equidistant from loop 13. Also, a button 30 substantially similar to button 22 is secured to garment 10 so that it may fit into loop 13 in the manner described above.

45 In use, belt 11 may be slipped through loops 12 and 13 until it occupies the position shown in Figure 1. Next, buttons 22 and 30 are passed through slots 14 and 29 and secured within loops 12 and 13. Belt 11 is now in its operative position and it will be seen that it may move about the robe within loops 12 and 13 in either direction a distance equal to substantially half the length of slots 14 and 29. However, belt 11 cannot be dislodged from either of the loops until buttons 30 and 22 are dislodged from loops 12 and 13 and slipped through the slots 14 and 29. Accordingly, belt 11 is reliably 55 retained in its operative position and yet may be easily removed when desired. It is also true that when belt 11 occupies the position shown in Figure 1, it is maintained in a substantially flatwise position with respect to robe 10 by loops 12 and 13 which are buttoned down upon the belt to prevent any rumpling or twisting of the belt. Reinforcing parts 24 and 25 cooperate to maintain loops 12 and 13 in their flattened position against the belt to help hold the belt in its flat position, but it 75 should be understood that many of the impor-

tant features of my invention may be achieved with straps having no such reenforcing parts.

5 Turning now to Figure 5, there is shown a belt portion generally indicated at 31 of another embodiment of my invention. Preferably belt 31 comprises two thicknesses 32 and 33 of material substantially similar to the material from which belt 11 is formed. Thus, belt 31 is provided with lines of stitches 34 along its opposite longitudinal edges. Formed in thickness 33 of belt 31 is a 10 slot 35 and, as better shown in Figure 6, a reenforcing part 36 is secured to the inner side of thickness 33 substantially adjoining slot 35. Reenforcing part 36 has formed therein a slot 37 substantially similar in dimensions to slot 35 and 15 in registry therewith. Preferably I provide a line of stitches 38 extending about reenforcing part 36 and through thicknesses 32 and 33. Accordingly, there is provided in belt 31 a slot 35 adjoining a longitudinal channel 41 bounded by reenforcing 20 part 36 and thickness 32. Furthermore, reenforcing part 36 is preferably formed from a semi-rigid flexible material as, for example, celluloid or whalebone, providing a smooth surface on one side of channel 41.

25 Belt 31 may be secured to a robe generally similar to robe 10 (Figure 1) either with or without loops, according to the particular requirements of use, a fragmentary portion of such a robe being indicated at 39 in Figure 6. Thus, a button 40 is secured to robe 39 substantially at the waist portion thereof by way of a shank 42 and, when belt 31 is in its operative position, shank 42 extends through slots 35 and 37 (Figure 6) so that button 40 is disposed within channel 41 resting 35 upon reenforcing part 36. Button 40 thus serves to hold belt 31 to robe 39 while permitting relative movement between the belt and the robe limited by the length of channel 41. Another channel and slot substantially similar to slot 35 and 40 channel 41 may be provided in belt 31 and the two channels may occupy positions substantially similar to the position of slots 14 and 29 in belt 11 (Figure 1). Of course, another button similar to button 40 is secured to robe 39 adjacent the other slot and the buttons also occupy positions with respect to the channels substantially similar to the relative positions of buttons 22 and 30 in Figure 1. In this manner, belt 31 is reliably secured to robe 39 while its longitudinal movement about the robe is limited. It will also be noted that belt 31 may be so secured to the robe without the aid of loops similar to loops 12 and 13 (Figure 1), although the provision of such loops on robe 39 has many advantages.

55 Referring now to Figure 7, there is shown another embodiment of my invention as applied to a robe generally indicated at 43. Thus I provide a vertical slot 44 in robe 43 having applied to its opposite edges a series of parts generally indicated at 45 constituting the fasteners of a slide fastening apparatus. Thus, a sliding element generally indicated at 46 fits over the opposite edges of slot 44 and may be moved along parts 45. Element 46 has a mouth portion 47 greater 60 in width than its opposite end 48, as better shown in Figure 8, so that as the element is moved in an upward direction, as viewed in the figures, it forces parts 45 into an interlocking position; there is a certain amount of frictional resistance to the movement of part 46 along slot 44 in either direction.

65 Secured to element 46 is a loop generally indicated at 49 comprising a relatively stiff base member 50 preferably formed from celluloid, 75

whalebone, or the like, and a strip 51 of flexible material preferably doubled over at its opposite ends and secured to base 50 by way of stitches 52.

Accordingly, a belt 53 passes through loop 49, 5 this belt being substantially similar in construction to belt 11 in Figure 1. Thus, as better shown in Figure 8, belt 53 is provided with a longitudinal slot 54, and a shank 55 (Figure 7) is secured to base 50 and element 46 to extend through slot 54. 10 A button 56 is connected to shank 55 so that it may be slipped through a suitable buttonhole 57 provided in strip 51. Thus, after belt 53 has been passed through loop 49, button 56 may be secured to strip 51 in the position shown in Figures 7 15 and 8.

Constructions similar to that described above may be applied to the opposite sides of the back portion of robe 43 in a manner substantially similar to the position of loops 12 and 13 and slots 14 20 and 29 shown in Figure 1. Thus, belt 53 is free to slide relative to the robe, being limited in its movement by the length of slot 54 and its corresponding slot in a manner substantially similar to the operation of belt 11 hereinabove described. 25 However, in this embodiment of my invention, the wearer may also achieve a vertical adjustment of the loops by merely pulling them in either direction. Thus, a vertical movement of loop 49 in either direction moves element 46 30 along slot 44. Furthermore, upon achieving a new position along slot 44, the frictional resistance to the movement of element 46 is sufficient to retain the loop in this new position. Accordingly, not only is the longitudinal movement of belt 53 limited and the belt maintained in a flat-wise position with respect to the robe, but, also, the vertical position of the belt and loops with respect to the robe may be changed at will.

Although the various embodiments of my invention have been hereinabove described as applied to a "robe" or the like, it should be understood that this invention has a much broader application and may be applied to all common forms of garments, as, for example, gowns, 45 dresses and coats.

It will thus be seen that I have provided several thoroughly practical and efficient constructions in which the several objects hereinabove mentioned as well as many others are successfully 50 achieved.

As many possible embodiments may be made of the above invention and as many changes might be made in the embodiment above set forth, it is to be understood that all matter hereinbefore set 55 forth or shown in the accompanying drawings is to be interpreted as illustrative and not in a limiting sense.

I claim:

1. In garment construction, in combination, 60 means forming a garment adapted to fit about a substantial portion of the body, a pair of loops spaced from each other and secured to the back portion of said garment substantially at the waist portion thereof, said loops being formed from double thicknesses of material, a substantially 65 flat belt extending through both of said loops and adapted to encircle said garment, said belt having longitudinal slots spaced from each other and substantially at right angles to said loops, reenforcing parts formed from relatively stiff material secured within said thicknesses of said loops, strips of material characterized by a smooth surface secured to the sides of said loops adjacent said belt and the portions of said garment 70 in registry with said loops to contact said

belt, shanks secured to said garment and each extending through one of said slots in said belt, and buttons secured to said shanks adapted to fit within suitable buttonholes formed in the under thickness of said loops whereby the longitudinal movement of said belt about said garment is limited and the belt is maintained in a flat position. 5

2. In garment construction, in combination, means forming a garment adapted to fit about 10 a substantial portion of the body, a pair of loops spaced from each other and secured to the back portion of said garment substantially at the waist portion thereof, said loops being formed from double thicknesses of material, a substantially 15 flat belt extending through both of said loops and adapted to encircle said garment, said belt having longitudinal slots spaced from each other and substantially at right angles to said loops, reenforcing parts formed from relatively 20 stiff material secured within said thicknesses of said loops, shanks secured to said garment and each extending through one of said slots in said belt, and buttons secured to said shanks adapted to fit within suitable buttonholes formed in the 25 under thickness of said loops whereby the longitudinal movement of said belt about said garment is limited and the belt is maintained in a flat position.

3. In garment construction, in combination, 30 means forming a garment adapted to fit about a substantial portion of the body, a pair of loops spaced from each other and secured to the back portion of said garment substantially at the waist portion thereof, said loops being formed from 35 double thicknesses of material, a substantially flat belt extending through both of said loops and adapted to encircle said garment, said belt having longitudinal slots spaced from each other and substantially at right angles to said loops, 40 strips of material characterized by a smooth surface secured to the sides of said loops adjacent said belt to contact said belt, shanks secured to said garment and each extending through one of said slots in said belt, and buttons secured to 45 said shanks adapted to fit within suitable buttonholes formed in the under thickness of said loops whereby the longitudinal movement of said belt about said garment is limited and the belt is maintained in a flat position. 50

4. In garment construction, in combination, means forming a garment, a pair of loops, means securing said loops to said garment so that said loops may be moved vertically with respect to said garment, a belt passing through said loops, 55 and means coaxing with said loops to limit the longitudinal movement of said belt with respect to said loops.

5. In garment construction, in combination, means forming a garment having a pair of vertical tracks therein, elements adapted to ride on said tracks, a pair of loops secured to said elements, a belt extending through said loops and having a pair of spaced slots adjacent said loops, and means connected to the opposite sides of 65 said loops and extending through said slots whereby the longitudinal movement of said belt with respect to said loops is limited and the vertical position of said loops and said belt with respect to said garment may be changed at will. 70

6. In garment construction, in combination, means forming a garment adapted to fit about a substantial portion of the body, a pair of loops spaced from each other and secured to the back portion of said garment substantially at the 75

- waist portion thereof, said loops being formed from double thicknesses of material, a substantially flat belt extending through both of said loops and adapted to encircle said garment, said 5 belt having longitudinal slots spaced from each other and substantially at right angles to said loops, said slots extending along said belt to points on the opposite sides of said loops substantially equidistant therefrom, strips of material characterized by a smooth surface secured 10 to the sides of said loops adjacent said belt to contact said belt, shanks secured to said garment and each extending through one of said slots in said belt, and buttons secured to said shanks adapted to fit within suitable button-holes formed in said loops whereby the longitudinal movement of said belt about said garment is limited and the belt is maintained in a flat 15 position.
- 20 7. In garment construction, in combination, means forming a garment adapted to cover a substantial portion of the body, a pair of loops secured to said garment at spaced points in the vicinity of the waist portion thereof, a flat belt 25 extending through said loops and adapted to encircle the body, said belt having a pair of spaced longitudinal slots formed therein substantially adjacent said loops and at right angles thereto, shanks secured to said garment and extending through said slots, and button members secured to said shanks and adapted to button 30 into suitable holes formed in said loops.
8. In garment construction, in combination, means forming a garment adapted to cover a substantial portion of the body, a pair of loops secured to said garment at spaced points in the vicinity of the waist portion thereof, a flat belt 35 extending through said loops and adapted to encircle the body, said belt having a pair of spaced longitudinal slots formed therein substantially adjacent said loops and at right angles thereto, and shanks secured to said loops and said garment and extending through said slots.
9. In garment construction, in combination, 40 means forming a garment adapted to cover a portion of the body, a pair of loops spaced from each other and secured to said garment at spaced points substantially at the waist portion of said garment, a belt extending through said loops and adapted to encircle said garment, said belt having spaced longitudinal slots formed therein substantially adjacent said loops, reenforcing parts formed from relatively stiff material secured to said loops, and shanks secured to said loops and said garment and extending through said slots.
10. In garment construction, in combination, means forming a garment adapted to cover a portion of the body, a pair of loops spaced from 45 each other and secured to said garment at spaced points substantially at the waist portion of said garment, a belt extending through said loops and adapted to encircle said garment, said belt having spaced longitudinal slots formed therein substantially adjacent said loops, strips of material characterized by a smooth surface secured to the under side of said loops to contact said belt, and shanks secured to said loops and said garment and extending through said slots.
11. In garment construction, in combination, means forming a garment adapted to cover a portion of the body, a pair of loops spaced from each other and secured to said garment at spaced points substantially at the waist portion of said garment, a belt extending through said loops and 50
- adapted to encircle said garment, said belt having spaced longitudinal slots formed therein substantially adjacent said loops, reenforcing parts formed from relatively stiff material secured to said loops, and shanks secured to said loops and said garment and extending through said slots, the portion of said garment in registry with said loops and the sides of said loops contacting said belt being formed from material having a relatively smooth surface. 55
12. In garment construction, in combination, means forming a garment, a belt adapted to encircle said garment when worn, said belt having a longitudinal slot of appreciable length formed therein, and means secured to said garment and extending through said slot to hold said belt to said garment while permitting longitudinal movement of said belt within limits. 60
13. In garment construction, in combination, means forming a garment, a flat belt adapted to encircle said garment when worn, said belt having formed therein a pair of spaced longitudinal slots of appreciable length, and elements secured to said garment and extending through said slots to hold said belt to said garment while permitting relative movement between said garment and said belt within limits. 65
14. In garment construction, in combination, means forming a garment, a flat belt adapted to encircle the waist portion of said garment, said belt having a pair of spaced longitudinal slots of appreciable length formed therein, means secured to said garment and extending through each of said slots, and buttons secured to said means to hold said belt to said last-mentioned means, said last-mentioned means adapted to contact with said slots to permit relative movement between said belt and said garment within limits. 70
15. In garment construction, in combination, means forming a garment, a belt adapted to encircle said garment and formed from double thicknesses of material, the thickness of said belt adjacent said garment having a longitudinal slot formed therein of appreciable length but shorter than the length of said belt, reenforcing means secured to said last-mentioned thickness adjacent said slot, and a button-like part secured to said garment and adapted to fit within said slot to hold said belt to said garment and permit longitudinal movement thereof within limits. 75
16. In garment construction, in combination, means forming a garment, a belt for said garment comprising two thicknesses of material, the thickness of said belt contacting said garment having a longitudinal slot formed therein shorter than the length of said belt, means comprising relatively stiff material secured to the inner side of said last-mentioned thickness substantially adjacent said slot, a shank secured to said garment and extending into said slot, and a button-like part secured to said shank and adapted to rest between the thicknesses of said belt and upon said last-mentioned means to hold said belt to said garment and permit relative movement between said belt and said garment within limits. 80
17. In garment construction, in combination, means forming a garment, a flat belt for said garment adapted to encircle the waist portion thereof and being formed from two thicknesses of material, the thickness of said material in engagement with said garment having spaced longitudinal slots formed therein, reenforcing parts secured to the concealed side of said last-mentioned thickness adjacent said slots, elements adapted to fit between said thicknesses of said 85
- garment, and shanks secured to said belt and said garment and extending through said slots. 90

5 belt, said elements being greater in size than the width of said slots and adapted to ride on said reenforcing parts, and means securing said elements to said garment whereby said belt is held in position on said garment and relative movement between said garment and said belt is limited.

10 18. In garment construction, in combination, means forming a garment, a belt adapted to encircle said garment when worn, said belt having formed therein a pair of spaced longitudinal slots of appreciable length, shanks secured to said garment and extending through said slots, and button elements secured to said shanks over said

slots to hold said belt to said garment while permitting longitudinal movement of said belt in either direction for a distance substantially corresponding to the length of one of said slots.

19. In garment construction, in combination, means forming a garment, a plurality of loops secured to said garment and capable of relative vertical movement with respect to said garment, a belt extending through said loops and adapted to encircle said garment, said belt having longitudinal slots formed therein, and shanks extending through said slots and secured to the opposite side portions of said loops. 10

ERNEST G. DANN.
